CONTROLLING APPARATUS FOR HIGHWAY
CROSSING SIGNALSGeorge R. Pflasterer, Swissvale, Pa., assignor to
The Union Switch & Signal Company, Swiss-
vale, Pa., a corporation of Pennsylvania

Application July 18, 1936, Serial No. 91,419

6 Claims. (Cl. 246—130)

My invention relates to controlling apparatus for highway crossing signals, that is, to apparatus for the control of signals which are placed at intersections of railways and highways for the purpose of warning users of the highway when a train is approaching.

I will describe five forms of apparatus embodying my invention, and will then point out the novel features thereof in claims.

10 Fig. 1 of the accompanying drawing is a diagrammatic view illustrating one form of apparatus embodying my invention as applied to a stretch of track over which traffic moves in both directions. Figs. 2, 3, 4, and 5 are diagrammatic views each illustrating a modification of a portion of the apparatus shown in Fig. 1 and each also embodying my invention.

Similar reference characters refer to similar parts in each of the several views.

20 Referring first to Fig. 1, the reference characters 1 and 2 designate the rails of a stretch of track over which traffic moves in both directions. The stretch is divided by insulated joints 3 into two adjacent sections designated by the reference characters 1T and 2T, respectively. Each track section is provided with a track battery 4 connected across the rails at one end of the section and with a track relay, designated by the reference character R with a prefix the same as the 25 reference character of the associated section, connected across the rails at the other end of the section. As here shown, the relays 1TR and 2TR are the magnets of an interlocking relay K. Located adjacent the junction of sections 1T and 2T is an intersection of the rails of the stretch and a highway H. The highway H is protected by a signal S of any suitable type. As here shown, the signal S includes a green lamp G for displaying a proceed indication, a yellow lamp Y for displaying a caution indication, and a red lamp R for displaying a stop indication. The signal S is controlled jointly by relay K and a relay XP having a slow releasing characteristic. The relay XP is controlled by the interlocking relay K.

40 With both sections 1T and 2T unoccupied so that both magnets 1TR and 2TR are energized, the relay XP is supplied with energy to cause such relay to assume its initial condition and, consequently, the green lamp G is energized. The circuit for relay XP may be traced from terminal B of any suitable source of energy over front "flagman" contact 6 of magnet 1TR, front "flagman" contact 7 of magnet 2TR, and relay XP to terminal C of the same source of energy. 45 The circuit for the green lamp G may be traced

from terminal B through front "flagman" contact 6 of magnet 1TR, front "flagman" contact 7 of magnet 2TR, front point of contact 8 of relay XP, and lamp G to terminal C.

I shall now assume that an eastbound train, that is, a train moving from left to right, enters section 1T so that magnet 1TR becomes released. When magnet 1TR is released, relay XP will become deenergized and back contact 9 of magnet 1TR will become closed. A circuit will then be completed for the yellow lamp Y to cause the signal to display the caution indication. The circuit for lamp Y may be traced from terminal B over back contact 9 of magnet 1TR, front point of contact 10 of relay XP, and lamp Y to terminal C. At the expiration of a given time interval, when relay XP attains its operated condition, a circuit will be completed for the red lamp R to cause the signal to display a stop indication. This circuit may be traced from terminal B over back contact 9 of magnet 1TR, back point of contact 10 of relay XP, and lamp R to terminal C. When the train vacates section 1T and enters section 2T, magnet 1TR will become energized and magnet 2TR will become deenergized. Because the relay K, however, is of the interlocking type, front "flagman" contact 7 of magnet 2TR will not become opened and back contact 11 of magnet 2TR will not become closed. Relay XP, therefore, will again assume its initial condition so that green lamp G will be energized over the previously traced circuit for this lamp. When the train departs from section 2T, the magnet 2TR will again become energized to restore all apparatus to its normal condition.

25 It will be understood that the release time of relay XP is such that the caution signal will be displayed for a length of time sufficient to give users of the highway ample warning before the display of the stop signal.

30 While I have described the operation of the apparatus shown in Fig. 1 for an eastbound train only, it will be readily apparent how the apparatus operates for a train moving in the opposite direction.

35 It will be noted that the caution lamp Y is provided with another circuit including the back point of contact 8 of relay XP. This circuit insures that the caution lamp will be lighted, when contacts 6 and 7 of relay K become closed, in the event that relay XP should fail to assume its initial condition to light the proceed lamp.

40 Referring next to Fig. 2, the reference character XPA designates a relay having a slow release characteristic which relay is controlled by

40

30

35

40

45

50

55

a front contact 12 of the relay XP. That is, relay XPA will assume its initial condition when relay XP is in its initial condition, and will assume its operated condition a predetermined time interval after relay XP attains its operated condition. This arrangement is sometimes useful when it is desirable to display the caution signal for a period of time greater than can be obtained by the release time of relay XP alone. The 10 lamps G, Y, and R are controlled by the relay K and relay XPA in a manner similar to that described for the apparatus shown in Fig. 1. That is, the green lamp circuit includes front "flagman" contacts 6 and 7 of magnets 1TR 15 and 2TR, respectively, and front point of contact 13 of relay XPA; the caution lamp circuits include either back contact 9 of magnet 1TR or back contact 11 of magnet 2TR and front point of contact 14 of relay XPA; and the red lamp 20 circuits include either back contact 9 of magnet 1TR or back contact 11 of magnet 2TR and back point of contact 14 of relay XPA. The yellow lamp Y is also provided with an auxiliary circuit, including the back point of contact 13 25 of relay XPA, for lighting that lamp in the event that relay XPA fails to assume its initial condition when contacts 6 and 7 of relay K are both closed.

Referring next to Fig. 3, the reference character TE designates a timing device here shown as a thermal relay. The relay TE is controlled by contacts 6 and 7 of relay K in the same manner as relay XP. That is, relay TE will assume its initial condition when energized by the closing of both front contacts 6 and 7 and will assume its operated condition a predetermined time interval after becoming deenergized by the opening of either contact 6 or contact 7. The green lamp G is provided with a circuit which includes both contacts 6 and 7 so that the lamp G will become lighted whenever both magnets 1TR and 2TR are picked up regardless of the condition of relay TE. The yellow lamp is provided with circuits which include either back contact 9 or back contact 11 of relay K and front contact 15 of relay TE. The red lamp R is provided with circuits which include either back contact 9 or back contact 11 of relay K and back contact 16 of relay TE. Contacts 15 and 16 will be so adjusted that contact 16 will become closed only when relay TE is in its operated condition and contact 15 will become closed when relay TE is in its initial condition and will remain closed until just before contact 16 becomes closed. The 55 signal S, therefore, will display the proceed indication when both contacts 6 and 7 are closed and will display either the caution indication or the stop indication, when either back contact 9 or back contact 11 of relay K becomes closed, depending upon whether contact 15 or contact 16 of relay TE is closed.

Referring now to Fig. 4, the reference character J designates a relay provided with a pickup magnet M₁ of comparatively low resistance and 65 with a holding magnet M₂ of comparatively high resistance. The relay J, as here shown, is provided with a dashpot designated by the reference character 17 which is operably connected to the relay armature 18 to cause that armature to be slow in releasing. Under normal conditions, that is, with both contacts 6 and 7 of relay K closed, relay J is energized over a holding circuit which passes from terminal B through front contact 6 of magnet 1TR, front contact 7 of magnet 2TR, magnet M₁ of relay J, front contact 19 of relay

J, and magnet M₂ of relay J to terminal C. When relay J is in its operated condition, a pick-up circuit is provided which includes front contacts 6 and 7 of relay K and back contact 20 of relay J. Contacts 19 and 20 are so adjusted that back contact 20 will not become opened before front contact 19 becomes closed. The pickup circuit for relay J, therefore, is of comparatively low resistance to cause a correspondingly strong attraction of the armature 18, but the holding circuit is of comparatively high resistance so that normally the current consumption of relay J is small. Relay J is provided with a contact 21 which is closed when relay J is in its initial condition and which remains closed until just before the relay attains its operated condition, and with a contact 22 which is closed only when the relay is in its operated condition. The relay J governs the yellow and green lamps in a manner similar to that just described for relay TE. That is, the yellow lamp is lighted over circuits which include front contact 21 of relay J and the red lamp is lighted over circuits which include back contact 22 of relay J.

Referring next to Fig. 5, the reference character Q designates in general a timing device which controls the yellow and red lamps Y and R in a manner similar to that just described for the relays TE and J in Figs. 3 and 4, respectively.

As here shown diagrammatically, the device Q comprises a motor 23, which when energized, rotates a camshaft, indicated by dotted line 24, in a counter-clockwise direction to wind-up by means of a pinion 25, a coiled spring 26 of a clockwork 27. Rotating with shaft 24 is a contact actuating cam 28. When shaft 24 is rotated counter-clockwise by motor 23 to wind-up the clockwork mechanism, cam 28 is rotated to the position shown in Fig. 5 when the device is in its initial or wound-up condition. When the wound-up condition is attained, the motor circuit is opened at contact 29-30 and the clockwork mechanism is then held latched in this condition by the energization of holding coil 31. The apparatus shown in Fig. 5, in so far as the control of contact 29-30 is concerned, is similar to contact 19 of United States Letters Patent No. 1,896,120, granted February 7, 1933, to Henry S. Young and Howell N. Dixon. The holding and operating circuits both include front contacts 6 and 7 of relay K and may very readily be traced. When holding coil 31 becomes deenergized, spring 26 will drive cam 28 in a clockwise direction so that at the expiration of a given time interval, contact 32-33 will become opened and contact 32-34 will become closed.

The contact 32-33 controls the yellow lamp Y and the contact 32-34 controls the red lamp R. The green lamp G is controlled in the usual manner by contacts 6 and 7 of relay K. That is, the green lamp G is lighted when both contacts 6 and 7 are closed and the yellow lamp Y or the red lamp R will become lighted, when either magnet 1TR or 2TR is released depending upon whether contact 32-33 or contact 32-34 is closed.

From the foregoing description of the apparatus embodying my invention, it will be seen that I have provided, at an intersection of a railway and a highway simple and reliable apparatus for displaying a proceed, a caution, and a stop signal in accordance with traffic conditions on the railway.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a stretch of railway track including an intersection with a highway, a track section included in said stretch so located as to become occupied by a train approaching said intersection, a track circuit including a track relay for said track section, a device capable of assuming an initial condition when energized and an operated condition a predetermined interval of time after becoming deenergized, means including a front contact of said track relay effective to energize or deenergize said device according as said track relay is picked up or released respectively, a signal located at said intersection, means effective to cause said signal to indicate proceed when said track relay is picked up provided said device is then in its initial condition, means effective to cause said signal to indicate caution or stop when said track relay is released according as said device is then in its initial condition or its operated condition respectively, and means also effective to cause said signal to indicate caution if said device remains in its operated condition when said track relay is picked up.

2. In combination, a stretch of railway track including an intersection with a highway, a track section included in said stretch so located as to become occupied by a train approaching said intersection, a track circuit including a track relay for said track section, a device capable of assuming an initial condition when energized and an operated condition a predetermined interval of time after becoming deenergized, means including a front contact of said track relay effective to energize or deenergize said device according as said track relay is picked up or released respectively, a signal located at said intersection and including a proceed lamp as well as a caution lamp and a stop lamp, a circuit for said proceed lamp including a front contact of said track relay and a contact which is closed when said device is in its initial condition, a circuit for said caution lamp including a back contact of said track relay and a contact which is closed when said device is in its initial condition, another circuit for said caution lamp including a front contact of said track relay and a contact which is closed when said device is in its operated condition, and a circuit for said stop lamp including a back contact of said track relay and a contact which is closed only when said device is in its operated condition.

3. In combination, a stretch of railway track including an intersection with a highway, a track section included in said stretch so located as to become occupied by a train approaching said intersection, a track circuit including a track relay for said track section, a signal at said intersection including a proceed indication unit as well as a caution indication unit and a stop indication unit, a slow releasing auxiliary relay which is energized or deenergized according as said track relay is picked up or released respectively, a circuit for said proceed indication unit including a front contact of said track relay and a front contact of said auxiliary relay, a circuit for said caution indication unit including a back

contact of said track relay and a front contact of said auxiliary relay, another circuit for said caution indication unit including a front contact of said track relay and a back contact of said auxiliary relay, and a circuit for said stop indication unit including a back contact of said track relay and a back contact of said auxiliary relay.

4. In combination, a stretch of railway track including an intersection with a highway, a track section included in said stretch so located as to become occupied by a train approaching said intersection, a track circuit including a track relay for said track section, a signal at said intersection including a proceed indication unit as well as a caution indication unit and a stop indication unit, a first auxiliary relay governed by said track relay in such a manner as to assume an initial condition when said track relay is picked up and an operated condition a predetermined time interval after said track relay is released, a second auxiliary relay governed by said first relay in such a manner as to assume an initial condition when said first relay is in its initial condition and an operated condition a predetermined time interval after said first relay attains its operated condition, means for energizing said proceed indication unit when said track relay is picked up provided said second auxiliary relay is then in its initial condition, means for energizing said caution indication unit when said track relay is released provided said second auxiliary relay is then in its initial condition, means also effective to energize said caution indication unit if said second auxiliary relay remains in its operated condition when said track relay becomes picked up, and means for energizing said stop indication unit when said track relay is released provided said second auxiliary relay is then in its operated condition.

5. In combination, a stretch of railway track including an intersection with a highway as well as a first track section so located as to become occupied by a train approaching said intersection from one direction and a second track section so located as to become occupied by a train approaching said intersection from the other direction, an interlocking relay including a first magnet which is energized only if said first section is unoccupied and a second magnet which is energized only if said second section is unoccupied, a timing device capable of assuming an initial condition when energized and an operated condition a predetermined time interval after becoming deenergized, means effective to energize said timing device provided both said magnets are picked up, a signal located at said intersection and including a proceed lamp as well as a caution and a stop lamp, means effective to energize said proceed lamp provided said timing device is in its initial condition when both said magnets are picked up, means effective to energize said caution lamp provided said timing device is in its initial condition when either magnet is released, means also effective to energize said caution lamp if said timing device remains in its operated condition when both said magnets are picked up, and means effective to energize said stop lamp provided said timing device is in its operated condition when either magnet is released.

6. In combination, a section of railway track including an intersection with a highway, a track circuit including a track relay for said section, a

slow release relay, a circuit for said slow release relay including a front contact of said track relay, a three-indication signal at said intersection, a proceed circuit for said signal including a front contact of said track relay and a front contact of said slow release relay, a caution circuit for said signal including a front contact of said track relay and a back contact of said slow release re-

lay, another caution circuit for said signal including a back contact of said track relay and a front contact of said slow release relay, and a stop circuit for said signal including a back contact of said track relay and a back contact of said slow release relay. 5

GEORGE R. PFLASTERER.
